J. TEIPEL

PULVERIZING MACHINE

Filed April 29, 1927

Fig. 1.

Fig. 2.

Fig. 3.

A technical cross-sectional drawing of a device. It features a central vertical column with various internal parts labeled with numbers. At the top, a part is labeled 'E'. Below it, a section is labeled '17'. To the left, a vertical column is labeled '18'. At the bottom, there are several labels: '10' and '2' on the right, '9' and '14' on the far right, '13' and '16' on the bottom right, '11' and '12' on the left, and '14' and '16' on the bottom left. The drawing uses hatching to distinguish different materials or layers.

UNITED STATES PATENT OFFICE.

JOSEPH TEIPEL, OF ST. LOUIS, MISSOURI, ASSIGNOR TO AMERICAN PULVERIZER COMPANY, OF ST. LOUIS, MISSOURI, A CORPORATION OF MISSOURI.

PULVERIZING MACHINE.

Application filed April 29, 1927. Serial No. 187,524.

This invention relates to a certain new and useful improvement in pulverizing or crushing machines.

My invention has for its chief object the provision in a machine of the class stated of a pivotally swingable grinding-plate and readily operable means for conveniently, efficiently, and positively shifting the plate adjustably relatively to the hammer-mechanism of the machine as may be desired in the particular grinding or pulverizing operations being carried on.

And with the above and other objects in view, my invention resides in the novel features of form, construction, arrangement, and combination of parts hereinafter described and pointed out in the claims.

In the accompanying drawing,

Figure 1 is a fragmental side elevational view, partly broken away and in section, of a grinding or pulverizing machine embodying my invention;

Figure 2 is also a fragmental side elevational view of the machine;

Figure 3 is a detail fragmental sectional view of the machine; and

Figure 4 is a partly broken end view of the machine.

Referring now more in detail and by reference characters to the drawing, which illustrates a preferred embodiment of, and which shows merely such parts of the entire machine as are directly associated with, my present invention (a fuller or more complete illustration of a machine of the type to which this invention especially pertains is given in the application of E. T. Roebke for patent for pulverizing machine, Serial No. 174,848, filed March 12, 1927), 1 designates an end wall and 2, 2, the spaced side walls of the base A of the casing or shell of the machine, which is adapted to rest upon a floor, foundation, or other place of support.

B designates the main shaft of the machine, which is journaled for rotation on boxes 3 disposed upon the base side walls 2, and C designates the hammer mechanism, the latter preferably and in the present illustration including a spider 4 mounted on and suitably keyed to shaft B and ring-hammers 5 supported by the spider 4 both for rotation with and relatively to shaft B, as in said application of E. T. Roebke more fully described.

Suitably disposed and fixed within the base A for cooperation with the hammer mecha-

nism C, is a grinding-surface or grate D, and forming substantially a continuation of the grate D and suitably pivoted, as at 6, upon base A for swingable movement relatively both to base A and the hammer mechanism, 60 is a concave or grinding-plate E formed or provided upon its outer face with outwardly presented preferably spaced lugs or bosses 7, 7, having flat end faces, as at 8, obliquely disposed to the base end wall 1. 65

In operative location relatively to the plate E, the base side walls 2 are formed with outwardly presented bosses or lugs 9 aligned transversely of the machine and apertured, as at 10, in registration. 70

Fitted for rotatory movement in the respective bosses 9, are cylindrical bushings or bearings 11 having shaft-openings 12 also aligned transversely the machine, but eccentrically disposed relatively to the apertures 10 of the bosses 9, each of the members or bearings 11 being laterally and annularly flanged at its outer end and thereby formed or provided with a disk or ring 13 adapted to abut at its inner end face flatwise upon the outer end face of the respective boss 9, as best seen in Figure 3. Preferably, for purposes shortly appearing, each boss 9 is provided in its outer end face with one or more tapped recesses, as at 14, and each ring or disk 13 is formed, in turn, with an annular series of openings 15. Adapted for insertion through some of the openings 15 to removably seat in the recesses 14 to both retain the bearings 11 in position and against rotatory movement, 80 are taps of cap-screws 16. 85

Disposed transversely of the machine for flatwise engagement and co-operation with the plate bosses 7, is a shaft 17 preferably of non-circular or rectangular section throughout, except at its opposite ends 18, at which ends the shaft 17 is of circular section and is disposed for support in the eccentric apertures 12 of the bearing-members 11, as best seen in Figure 3. 95

As best seen in Figure 1, the concave E rests at its lugs 7 upon and is thus supported at its free or lower end by the shaft 17 for co-operation with the hammer-rings 5. To shift the concave or plate E relatively to the rings 5 to meet the conditions or requirements of the crushing or pulverizing operations being carried on, the taps 16 are removed and the rings or disks 13 then, by means of a spanner-wrench or other suitable tool (not 100 105 110

shown) engaged with openings 15 thereof, rotarily actuated in one or the other direction, with the result that the shaft 17 will be shifted obliquely relatively to the lugs 7 and the plate or concave E consequently shifted pivotally toward or from the hammers 5.

Thus, in a simple, facile, and convenient manner, adjustments of the concave E may be effected to meet grinding or pulverizing requirements.

Pivotedly fastened, as at 19, to the plate E and projecting endwise therefrom through the base end-wall 1, is a bolt 20, disposed upon the threaded free end of which, are nuts or the like 21 adapted for impingement upon the base wall 1 to retain the plate E against the shaft 17 in any of its adjusted positions.

I am aware that changes in the form, construction, arrangement, and combination of the various parts of my new adjustable grinder-plate may be made and substituted for those herein shown and described without departing from the nature and principle 25 of my invention.

Having thus described my invention, what I claim and desire to secure by Letters Patent is:

1. In combination, in a machine of the class described, a casing, bosses oppositely presented outwardly from the side walls of the casing, said bosses having circular apertures aligned transversely of the machine, a hammer-mechanism mounted for operation within the casing, a grinding-plate mounted for adjustable movement pivotally within the casing in co-operative relation to the hammer-mechanism, and means for adjustably shifting the plate pivotally relatively to the hammer-mechanism, said means including cylindrical bushings mounted for rotatory movement in the apertures of the bosses and having openings aligned transversely of the machine and eccentrically disposed to the apertures of the bosses, spaced lugs projecting from the outer face of said plate, each of said

lugs having a flat end-face obliquely disposed to the end wall of the casing, and a shaft extending transversely of and through the casing and having its ends disposed in the openings of the bushings, the shaft intermediate its ends being of non-circular section for flatwise plate-supporting engagement with the flat end-faces of said lugs, said shaft being shifted obliquely relatively to the lugs and 55 said plate being shifted pivotally on rotatory actuation of said bushings.

2. In combination, in a machine of the class described, a casing, bosses oppositely presented outwardly from the side walls of the casing, said bosses having circular apertures aligned transversely of the machine, a hammer-mechanism mounted for operation within the casing, a grinding-plate mounted for adjustable movement pivotally within the 65 casing in co-operative relation to the hammer-mechanism, and means for adjustably shifting the plate relatively to the hammer-mechanism, said means including cylindrical bushings mounted for rotatory movement 70 in the apertures of the bosses and having openings aligned transversely of the machine and eccentrically disposed to the apertures of the bosses, spaced lugs projecting from the outer face of said plate, each of said lugs 75 having a flat end-face obliquely disposed to the end wall of the casing, a shaft extending transversely of and through the casing and having its ends disposed in the openings of the bushings, the shaft intermediate its ends 80 being of non-circular section for flatwise plate-supporting engagement with the flat end-faces of said lugs, and tool-engageable and bushing-actuated disks fixed on the bushings and abutting the outer end face of said 85 bosses, said shaft being shifted obliquely relatively to the lugs and said plate being shifted pivotally on rotatory actuation of said bushing-disks.

In testimony whereof, I have signed my 90 name to this specification.

JOSEPH TEIPEL.
